(57) **CLAIM**

The ornamental design for an electrical connector for refrigeration valve, substantially as shown and described.

DESCRIPTION

FIG. 1 is a front, top perspective view of an electrical connector for refrigeration valve comprising a new, original and ornamental design;

FIG. 2 is a bottom view thereof;

FIG. 3 is a top view thereof; and,

FIG. 4 is a front view, with the rear, right-hand side and left-hand side views being mirror images thereof.

The broken line portion of the figure drawings is included to show portions of the article that form(s) no part of the claimed design.

1 Claim, 4 Drawing Sheets

FIG. 1

FIG. 2

FIG. 3

FIG. 4
